John J. Keal, Los Angeles, Calif., assignor to Modeline
Company of California Inc., Los Angeles, Calif., a corporation of California

Application September 10, 1959, Serial No. 57,502

Term of patent 14 years

The rear and side of the lamp base which are not shown are the same as the front and opposite side shown.

The center panel is stippled to show contrast.

I claim:

The ornamental design for a lamp base or similar article, as shown and described.
